UNITED STATES PATENT OFFICE.

DANIEL JOHN O'LEARY, OF BRUFF, IRELAND.

TRAVELING-RUG AND FASTENING THEREFOR.

1,335,524.

Specification of Letters Patent. Patented Mar. 30, 1920.

Application filed July 28, 1919. Serial No. 313,813.

To all whom it may concern:

Be it known that I, DANIEL JOHN O'LEARY, a subject of the King of Great Britain, residing at Bruff, Co. Limerick, Ireland, have 5 invented certain new and useful Improvements in Traveling-Rugs and Fastenings Therefor, of which the following is a specification.

My invention relates to improvements in 10 traveling rugs and fastenings therefor, and comprises improvements on my former inventions described in specifications Nos. 1,242, 717 and 1,261,429, and my present invention has for its object to provide means whereby 15 engagement of the special buckle with the U-shaped fastener is made more secure while still providing for rapid manipulation, as more fully described hereinafter.

According to my present invention, the 20 improvements in traveling rugs and fastenings therefor are substantially the same as shown, described and claimed in my former Patent 1,261,429, but with the useful addition of the special buckle having an 25 elbow or V-shaped protuberance adapted to engage in a correspondingly shaped recess in the U-shaped fastener of said rug, so that when the rug is in the lapped position when in use, the engagement of the special buckle 30 and strap with the U-shaped fastener is made much more secure and is prevented from accidentally disengaging or partially disengaging as might easily happen under 35 jolts or jars when engagement is made between the special buckle and the U-shaped fastener if the fastening happened to be more or less slack without the improvements set forth herein.

In the accompanying drawing, Figure 1 40 shows a plan view of said rug, strap and fastening and component parts in the lapped position. Fig. 2 shows an elevation of the rug and fastening complete. Fig. 3 shows an elevation of said rug and fastening with 45 component parts in a spread out position. Fig. 4 shows a side elevation of the special buckle, and Fig. 5 an end elevation of same. Fig. 6 shows a side elevation of the U-shaped fastener, and Fig. 7 an end elevation 50 of same. The same reference numbers are used for the same parts.

The rug 1 is adapted to lap approximately one and a half times around the wearer, and is provided on the rear of the 55 waist line with a strap 2 and a reinforcing strip 5, both of which are riveted at 3 by

rivets 4, or sewn on to said rug, said strap having spaced elongated holes 5' adapted to engage in a headed projection or protuberance 6 of a special buckle 7 which latter 60 is slotted at 8 to receive said strap; and to the front portion of the rug at 9 is fixed by means of rivets 10 and a reinforcing strip 11, the fastener 12 which is U-shaped at 13, as shown in Fig. 7, the open end of which is 65 placed up or down, as desired, to engage with or disengage from the strap 2.

The essential features of improvement according to the present invention comprise the combination with the traveling rug of 70 a strap such as 2 with a special buckle such as 7, having an elbow or V-shaped protuberance 14' adapted to frictionally engage at 14 in a correspondingly shaped recess 14'' in the U-shaped fastener 12, fixed to said rug, 75 so that greater security in fastening is assured owing to the fact that the elbow or V-shaped protuberance 14' of the buckle 7 in the recess 14'' prevents any unintentional disengagement while at the same time rapid 80 disengagement is attained when desired by slightly separating the buckle from the fastening until the point of the elbow or V-shaped protuberance just clears the fastening.

The reinforcing strip 11 is further secured to the rug 1 by sewing on to same at 15. The outer end of the strip 2 is provided with a guard ring 16 having the known kind of spring-catch 17, so that said 90 guard ring may be easily attached to or detached from said strap, this guard ring being for the purpose of preventing the special buckle 7 from falling off said strap by gravity when disengaged from said elongated holes. As shown, the fastener 12 is flanged and holed at 18 for fastening to 95 said rug. By means of the U-shaped fastener 12, which may be inverted, the strap 2 may be rapidly inserted into or detached 100 from the U-shaped slot at 13 so that greater safety is insured in cases of emergency as when driving in the carriage of a runaway horse, while by means of the special buckle 7 any adjustment is easily made by shifting 105 the head 6 to any elongated hole 5' which latter insures an easy attachment to or disengagement from said strap and with greater security owing to the narrower portion of the elongated hole gripping the lower portion of the head or projection 6 when in the operative position as in Figs. 1 and 2. Said

rug is preferably made of some water-proof material and lined with some soft and warm material on the inside, and said fastening with component parts may be made of any suitable material. Said fittings or fastenings are intended for all classes of traveling rugs.

Having described my invention, what I claim is:—

10. A combined rug and fastening therefor comprising a rug adapted to lap approximately once and a half around the wearer, a strap with reinforcing strip riveted at one end to said rug, said strap having elongated spaced holes, a guard ring at the opposite end of said strap, a special buckle having

an elbow or V-shaped protuberance and slotted to receive said strap and headed to engage with said elongated holes therein, a U-shaped fastener having a corresponding 20 V-shaped recess adapted to frictionally engage with said elbow or V-shaped protuberance, said U-shaped fastener being fixed to said rug and adapted to engage with said strap and with said elbow or V-shaped protuberance of said special buckle, substantially as herein described. 25

Signed by me this ninth day of July, 1919.

DANIEL JOHN O'LEARY.
